Albert Edgar Blackman
By his Attorney
Emanuel Scheyer.

UNITED STATES PATENT OFFICE.

ALBERT EDGAR BLACKMAN, OF MOUNT VERNON, NEW YORK.

MAIL BOX.

Application filed February 16, 1927. Serial No. 168,632.

The invention relates to a mail-box having a series of individual compartments with two means of access. One means of access, an upper door which extends over all the compartments at once, is for the use of the postman in depositing the mail, the other means, a separate lower door for each compartment, is for the individual to whom the compartment has been assigned. There is one lock 10 for the upper door, while each lower door has its special lock.

An object of my invention is the simplification of the construction of the various parts of the box to facilitate their manufacture and 15 their assembling. An object is the construction of all the doors whereby they can be assembled as a single unit and this unit fastened to the front of the box. There is no panel strip, as is common in mail-box construction, 20 between the master door and the individual or tenant doors. The tenant doors may also be arranged to have no panel strips between them. The advantage of the assembled door 25 unit is that, the frame encompassing the doors can be assembled around the unit, said frame being formed of individual strips. Mail-boxes having rectangular frames formed of one piece require careful fitting of the doors in the frame, whereas a frame 30 formed of individual strips can be set around the door unit so as to fit it and held in proper position while being spot welded or otherwise fastened to the box. In my preferred form the tenant doors are hinged 35 mounted upon the master door and hang from it, all the doors pivoting about a common axis. The master door is pivotally mounted upon substantially the front of the 40 box instead of having its pivot pass through apertures in the partition walls between the compartments or have its pivot pass through apertures in the sidewalls of the box as has been done heretofore. Where the pivot 45 passes through apertures in the box, it is not feasible to assemble the doors into one unit before fastening them upon the box. My mounting upon the front of the box permits 50 all the doors to be assembled into one unit before being attached to the box.

Other objects and advantages will become apparent from a further study of the description and drawing in which:

Figure 1 is a front elevation of my box, Figure 2 is a section of the box taken along the line 2-2 of Figure 1, Figure 3 is a side

elevation of the box looking along the line 3-3 of Figure 1, Figure 4 is a partial section, to an enlarged scale, of the box taken along the line 4-4 of Figure 1 and shows the detail of the fastening of a pivot rod to the front of the box, Figure 5 is an enlarged fragmental front elevation of the fastening of a pivot rod to the front of the box looking along line 5-5 of Figure 3, Figure 6 is a partial horizontal section taken along the line 6-6 of Figure 1, Figure 7 is a front elevation of a modified form of the box and Figure 8 is a partial section taken along the line 8-8 of Figure 7 and Figure 9 is a partial section taken similarly to Figure 4 showing a modified form for mounting the door unit. 60

The box is formed of back 10, top 11, bottom 12 and sidewalls 13 (Figures 2 and 3). Top and bottom 11 and 12 are formed with front flanges 14, while sidewalls 13 are provided with front flanges or laterally extending portions 15. Partition walls 16 divide the box into individual compartments. In Figure 1, partition walls 16 are shown only for the upper half of the box for the sake of clarity in the drawing, but they extend down to bottom 12 as shown in Figure 2. Master door 17 is provided with hinge ears 18 and 19, while the tenant doors 20 and 24 are provided with hinge ears 21 and 25. Tenant doors 20 are hung from master door 17 by means of pivot pins 22 which extend through ears 18, 22 and 19, while tenant door 24 is hung by pivot pin 23 which extends through ears 19 and 25. 70

The use of separate pivot pins has a great advantage in assembling the doors over the use of a single full length pivot pin as has been done heretofore. The friction necessary to overcome, in inserting the individual pins 80 is less than with a single long pin, especially when there is any irregularity in the alignment of the hinge ears. 85

After all the doors have been assembled into a single unit by means of pins 22 and 23, 100 it is to be noted that the outer ends of pins 22 will project beyond the sides of master door 17. Instead of using separate pins, a single rod can be used of a length sufficient to extend beyond the sides of the master door. This would also permit the doors to be assembled into a single unit and then fastened to the box. 105

The front frame of the box is composed of four strips, an upper strip 26, a lower strip 110

27 and side strips 28. In one method of assembling, the preferred one, the door unit, with pins 18 projecting beyond the edges of master door 17 is laid upon the front of the box in the position it is to occupy in the completed structure. Shim blocks 30 (Figures 1, 4 and 5) are fastened to flanges 15 so as to come under the outer ends of pins 18, said blocks being of such thickness so as to cause 10 the front face of the door unit to lie substantially in a plane, the upper edge of master door 17 coming against upper flange 14, while the lower edges of tenant doors 20 and 24 come against lower flange 14. The strips 26, 15 27 and 28, forming the front frame, are then placed about the edges of the door unit and welded or otherwise fastened to flanges 14 and 15. It is to be noted that each strip 28 is formed with a loop or bulge 29 adapted to 20 come over pins 22 and that a lip 31 is pressed down from the outer edge of the loop to prevent outward lateral movement of pins 22. Shim blocks 30 can be omitted and the pivot pins directly mounted upon the front of flanges 15, by causing hinge ears 18, 19, etc. to bulge slightly inward of the doors. A pivot pin resting directly against the front of flanges 15 is seen in Figure 7.

30 The hinge ears 18 and 19 project outwardly from the box or may bulge but slightly inward and thereby avoid the objection heretofore present in mail box constructions of inwardly projecting hinges or hinge devices which tend to catch or interfere with any 35 mail deposited in the box.

With the present construction the doors and front frame strips are assembled from 40 standardized pieces cut to size. No careful machining and fitting is required, as the strips forming the front frame can be placed around the door unit to suit. It also makes it a simple matter to supply a mail box with push buttons at the bottom, such as shown at 32 or with mouth pieces at the top as at 33 by 45 providing wider strips across the bottom and top than for boxes without these features. It is to be noted that no front panel pieces are provided between the tenant doors and between the master door and the tenant doors. 50 This allows the whole front of each compartment to be available for the deposit and withdrawal of mail. With other types of boxes in present use, the original blank in the whole front must be changed and taken into 55 consideration when providing for these special features.

Lock 34 is provided for the master door and individual locks 35 are provided for the tenant doors.

60 In the modified form of box shown in Figures 7 and 8, instead of forming the hinge ears upon the doors, said doors are cut in plain rectangles and a continuous hinge member 36 is welded or otherwise fastened 65 to the doors. This hinge member is the

well known piano or phonograph cabinet type of hinge. The hinge rod 37 extends beyond the sides of the door unit and is held in place upon flanges 15^a by strips 28^a formed similarly to strips 28 noted above. No block 70 such as 30 (Figure 4) is required, rod 37 coming directly against flanges 15^a. Instead of using a continuous rod 37 it can be broken up into lengths. Also upper and lower hinge straps 38 and 39 can be in multiple lengths. 75

Instead of mounting pivot pins 22 as shown in Figures 3 and 4, they can be mounted as shown in Figure 9, which is a section taken similarly to Figure 4. The side flanges 15^b of the box are looped inwardly of the box, 80 strips 28^b holding pivot pin 22 in place in the loop. In this construction, strips 28^b are substantially straight, no loop as at 29 (Figure 4) being required. Hinge ears (not shown) such as 18, 19, 21 and 25 project inwardly 85 of the doors instead of outwardly as in Figure 2.

In general it is to be noted that the door unit with its projecting pins can be placed as a whole against the front of the box in 90 any of the above mentioned types.

A box has been shown with three tenant doors, but boxes with additional compartments and tenant doors lend themselves as well to my construction. Also instead of using a box divided into compartments by partition walls, a box can be formed of separate receptacles, one for each compartment and fastened together as is well known in the art. 95

I claim:—

1. A mail box comprising a plurality of compartments opening at the front, a door unit mounted on the front of the box for closing said compartments, said door unit comprising a master door adapted to close the upper portions of said compartments, and tenant doors, one for each compartment, pivotally mounted at their upper ends upon the lower end of said master door for closing the lower portions of said compartments, and pivot means mounted upon the sides of the box with its axis forward of the front of the sidewalls of the box for pivotally supporting the master door at its lower corners. 110

2. A mail box comprising a plurality of compartments opening at the front, a master door pivotally mounted at its lower end upon the box, adapted to close the upper portions of said compartments, tenant doors, one for each compartment, pivotally mounted 115 at their upper ends upon the lower end of said master door for closing the lower portions of said compartments, and pivot means for providing the pivotal connection between the master door and tenant doors and the master door and the box, the axis of said means being forward of the rear face of said doors, portions of said means projecting beyond the sides of the master door and being mounted upon the sides of the box with its 120

pivotal axis forward of the front of the sidewalls of the box.

3. A mail box provided with a plurality of compartments, said box having its sidewalls provided with laterally extending flanges, a master door for closing the upper portions of said compartments and a plurality of tenant doors for closing the lower portions of said compartments, there being one of said latter doors for each compartment, the master door being pivotally mounted near its lower end upon the front of said flanges and the tenant doors being pivotally mounted near their upper edges, the mounting for all of said doors having a common pivotal axis.

4. A mail box comprising a plurality of compartments opening at the front, a master door pivotally mounted at its lower end upon the box, adapted to close the upper portions of said compartments, tenant doors, one for each compartment, pivotally mounted at their upper ends upon the lower end of said master door for closing the lower portions of said compartments, pivot means for providing the pivotal connection between the master door and tenant doors and the master door and the box, said means projecting beyond the sides of the master door and being mounted upon the sides of the box with its pivotal axis forward of the front of the sidewalls of the box, and a front frame for the box adapted to encompass all the doors, said frame having side members provided with bulged out portions adapted to come over the projecting portions of the pivot means.

5. A mail box provided with a plurality of compartments, a master door for closing the upper portions of said compartments, tenant doors, one for each compartment for closing the lower portions of said compartments, the master door being provided at its lower end with a plurality of aligned hinge ears projecting forward of the front face of the door, each tenant door being provided with a hinge ear projecting forward of its front face at its upper end, the ears of the master and tenant doors being suitably formed and spaced to dovetail together, pivot means extending through the ears and projecting beyond the sides of the master door, the sidewalls of the box being provided with laterally extending portions at their forward ends adapted to support said projecting portions of the pivot means.

6. A mail box comprising a plurality of compartments opening at the front, a door unit for the front of the box comprising a master door adapted to close the upper portions of the compartments and tenant doors, one for each compartment, pivotally mounted at their upper ends upon the lower end of the master door for closing the lower portions of said compartments, the sidewalls of said box being provided with laterally pro-

jecting portions, pivot means carried by the master door at its lower end and projecting beyond its sides, said door unit as a whole being placed upon the front of the box with the projecting portions of said pivot means coming against the front of the laterally projecting portions of said sidewalls, and a front frame for said box comprising top, bottom and side strips adapted to be individually assembled about said door unit, the side strips coming over the front of the projecting portions of the pivot means for retaining them in place against the laterally projecting portions of the sidewalls.

7. A mail box comprising a plurality of compartments opening at the front, the sidewalls of said box being provided with laterally projecting portions, a master door pivotally mounted at its lower end upon the box, adapted to close the upper portions of said compartments, tenant doors, one for each compartment, pivotally mounted at their upper ends upon the lower end of the master door for closing the lower portions of said compartments, pivot means for providing the pivotal connection between the master door and tenant doors and the master door and the box, said means projecting beyond the sides of the box forward of the laterally projecting portions of the sidewalls, and shim blocks interposed between the projecting portions of the pivot means and the projecting portions of the sidewalls.

8. In a mail box having a plurality of compartments and a plurality of adjacently and hingedly mounted doors for closing said compartments, hinge construction comprising hinge ears upon one end of said doors, said ears being in alignment and extending across the box, and pivot pins inserted through adjacent ears for pivotally fastening the doors together, the outside pivot pins extending beyond the sides of the outermost doors, the extending portions of said outside pins supporting the doors as a whole upon the box.

9. In a mail box having a front frame with top, bottom, and side members encompassing a master door and a plurality of tenant doors, pivot means for providing the pivotal mounting of the master door upon the box, said means projecting beyond the sides of the master door, and engaging means at the front of said side members for holding the projecting portions of said pivot means to the box, with the axis of said pivot means forward of the front of the sidewalls of the box.

10. In a mail box having a plurality of compartments open at the front with a master door hingedly mounted at its lower end for closing the upper portions of said compartments and tenant doors hingedly mounted at their upper ends for closing the lower portions of said compartments, the sidewalls of said box being provided at the front with laterally extending flanges, a front frame for

encompassing all of the doors comprising top, bottom and side strips adapted to be individually assembled and adjusted to the outline of the doors, the side strips being fastened 5 to said flanges and engaging means on said side strips for holding the pivotal mounting of said doors forward of said flanges.

11. A mail box comprising a plurality of compartments opening at the front, laterally 10 extending flanges provided at the front of the sidewalls of the box, a master door for closing the upper portions of said compartments, tenant doors, one for each compartment, pivotally mounted at their upper ends upon the 15 lower end of the master door for closing the lower portions of said compartments, and

pivot means for providing pivotal connection between the master and tenant doors and between said doors and the box, said pivot means projecting beyond the sides of the master door, a front frame for said box comprising top, bottom and side strips adapted to be individually assembled about all of the doors with the side strips fastened upon the front of said flanges, and engaging means on said side strips for holding the projecting portions of said pivot means forward of said flanges.

Signed at New York, in the county of Bronx and State of New York this 11th day 30 of February, A. D. 1927.

ALBERT EDGAR BLACKMAN.
